Scheiner et al., Parent U.S. Appl. No. 29/371,116, filed Oct. 27, 2010.

Primary Examiner — Charles D Hanson

(74) *Attorney, Agent, or Firm* — Nixon & Vanderhye P.C.

(57) **CLAIM**

The ornamental design for nasal prongs, as shown and described.

DESCRIPTION

FIG. 1 is a front perspective view of nasal prongs according to an embodiment of our design;

FIG. 2 is a reverse perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a front perspective view of nasal prongs according to a second embodiment of our design;

FIG. 10 is a reverse perspective view thereof;

FIG. 11 is a front view thereof;

FIG. 12 is a rear view thereof;

FIG. 13 is a top view thereof;

FIG. 14 is a bottom view thereof;

FIG. 15 is a left side view thereof;

FIG. 16 is a right side view thereof;

FIG. 17 is a front perspective view of nasal prongs according to a third embodiment of our design;

FIG. 18 is a reverse perspective view thereof;

FIG. 19 is a front view thereof;

FIG. 20 is a rear view thereof;

FIG. 21 is a top view thereof;

FIG. 22 is a bottom view thereof;

FIG. 23 is a left side view thereof; and,

FIG. 24 is a right side view thereof.

Throughout the various figures of the drawings, certain views may not be provided. The omission of a particular view is intended to convey that the element(s) depicted is/are plain and unornamented in that omitted view, or that the particular ornamental appearance in that view is simply not claimed.

Where included, the use of stippling and shading is provided to show contrast in materials to differentiate between dif-

(Continued)

ferent areas of the design. The claimed design is not limited to the illustrative use of stippling and/or shading.
